[57] CLAIM

The ornamental design for an insulated container assembly, as shown and described.

DESCRIPTION

FIG. 1 is a front elevational view of an insulated container assembly showing my new design; the sides not shown being substantially the same as that shown;

FIG. 2 is a top plan view thereof;

FIG. 3 is a bottom plan view thereof;

FIG. 4 is a top plan view of the base portion of the outer container with the lid removed;

FIG. 5 is a bottom plan view of the lid of the outer container;

FIG. 6 is a top plan view of the base portion with the inner container positioned within;

FIG. 7 is a partial sectional view of that shown in FIG. 1;

FIG. 8 is a front elevational view of the inner container shown separately for clarity of illustration;

FIG. 9 is a bottom plan view of that shown in FIG. 8;

FIG. 10 is a side elevational view of the plug for the inner container shown separately for clarity of illustration; and

FIG. 11 is a bottom plan view of that shown in FIG. 10.
